UNITED STATES PATENT OFFICE.

EDWARD ZEMAN, OF WOODSIDE, NEW YORK.

SWITCH LOCK.

Application filed June 16, 1923. Serial No. 645,712.

To all whom it may concern:

Be it known that I, EDWARD ZEMAN, a citizen of the United States, residing at Woodside, county of Queens, State of New York, have made a certain new and useful Invention in Switch Locks, of which the following is a specification.

This invention relates to a new and useful improvement in an electric switch and 10 more particularly to an electric switch in the form of a combination lock.

The object of the invention is to provide an electric switch for closing a circuit which can only be operated to close the circuit by 15 a person who is familiar with the combination of contacts to which the terminals of the electric wires are connected.

A further object of the invention is to provide a switch of this character which is 20 simple and inexpensive in construction and which may be used in any place where it is desired that the making and breaking of an electrical circuit should be under the control of certain parties only.

25 Other objects of the invention will appear more fully hereinafter.

The invention consists substantially in the construction, combination, location and 30 relative arrangement of parts, all as will be more fully hereinafter set forth, as shown in the accompanying drawing and finally pointed out in the appended claims.

Referring to the accompanying drawing:

Fig. 1 is an elevation of the front face 35 of the device.

Fig. 2 is a central vertical longitudinal sectional view of same on the line 2-2 of Fig. 1.

Fig. 3 is a sectional view taken on the 40 line 3-3 of Fig. 2 looking in the direction of the arrows.

Fig. 4 is an elevation of the front face of the contact plate showing two of the switch arms.

45 Fig. 5 is a detail sectional view showing the means of securing the contact point in one of the contact arms of the switch.

Referring specifically to the drawing, 1 designates a suitable housing which incloses 50 the switch mechanism in any suitable manner.

The switch structure proper is composed 55 of the contact plate 2 and the top plate 7.

The contact plate 2 is made of bakelite or 60 other suitable insulated material and is

separated or spaced from the top plate by means of a plurality of posts 8 which are secured to the contact plate and top plate in any suitable manner.

The inner face of the contact plate 2 has 60 a series of indentations 3 provided therein. These indentations are preferably arranged in a circle and there are three rows of the same.

At predetermined points on the contact 65 plate contact points are placed in these indentations and are maintained therein by means of binding posts to which said contact points are secured. These binding posts are indicated at 10, 11, 12, 13, in Fig. 2. 70

The wires 5 and 6 and 6^a of the circuit to be operated by the switch are adapted to be secured to said binding posts, wires 5 being adapted to be secured to certain of the posts and wires 6 and 6^a to certain other 75 of these posts, as will be more fully explained hereinafter.

Rotatably mounted in the top plate 7 is the shaft 9. Secured to the outer end of this shaft is the dial 14 and knob 15. Secured 80 to the inner end of said shaft is the contact arm 16.

The top plate is also provided with extensions 17 which are provided with openings 18 adapted to receive bolts or other 85 suitable fastening means for securing the switch to the place wherever it is to be used.

The dial 14 mounted on the shaft 9 has a series of numbers indicated thereon which are arranged to correspond with the number 90 of indentations arranged in three circles on the contact plate.

The contact arm 16 secured to the shaft 9 has secured to it at its free end an insulated contact mounting 19 which has two spring 95 maintained contact points 20 and 21. The method of mounting these contact points in the said mounting is shown in Fig. 5. The contact mounting 19 may be secured to the contact arm 16 in any suitable manner, such 100 as, for instance, by means of a screw 22. The contact points 20 and 21 are adapted to register with the middle row of indentations in said contact plate.

Rigidly mounted in the contact plate 2 105 is a shaft 23 which is secured thereto in any suitable manner, such as by a nut 24. Rotatably mounted on said shaft 23 are two contact arms 25 and 26. The free ends of these contact arms are bent so as to form 110

2
contact points to engage with the indentations on the contact plate 2. The contact arm 26 is shorter than the contact arm 25 and the contact point of this arm engages 5 the inner circle of indentations 3 on the contact plate. The contact point of the arm 25 engages the outer indentations on the contact plate. The contact arm 26 is of such length that the contact arm 16 may be revolved by the shaft 9 and the contact mounting 19 will pass the said contact arm 26 without interfering with the same.

At predetermined points in the three circular rows of indentations in the contact plate, there is inserted through the plate, at 15 the point where an indentation occurs, a contact pin. One pin, for instance, is placed at 27 in the outer row of indentations; two pins are placed at 28 in the middle row of 20 indentations, and one pin is placed at 29 in the inner row. These pins are secured to and maintained in place by means of the binding posts 13, 12, 11 and 10 as shown in Fig. 2.

Secured to the binding post 10 is a wire 5 leading to the electric current supply to be controlled, which may be the positive lead of said circuit. Secured to the binding post 12 is the wire 6^a which may be the negative lead for said circuit. The binding posts 11 and 13 are connected to wires leading to the apparatus to be controlled by the electric circuit such as for instance a bell, as shown in Fig. 2.

From the above description it will be seen that when the contact points of arms 16, 25 and 26 coincide with the contact pins 28, 29 and 27, the circuit is closed and the circuit may be employed for whatever purpose it is designed to be used. If any one of the contacts is out of engagement with its respective contact pin the circuit is broken and the electrical supply cut off.

In operation the switch operates as follows:

The dial 10, as above stated, is provided with numbers on the face thereof which correspond to the number of indications in the contact plate 2. The contact pin 29, for 50 instance, is inserted through the contact plate at a point on the inner circle of indentations which corresponds with the number 29 on the dial. The contact point 27 is inserted through the contact plate at a point 55 on the outer circle of indentations which corresponds to the number 27 on the dial, and the contact points 28 are inserted through the contact plate at points in the middle circle of indentations which correspond to the number 28 on the dial.

By revolving the dial in one direction, say to the left, the contact arm 16 is also caused to be revolved and the contact mounting 19 secured to the contact arm 16 is caused to 65 abut against and carry with it the contact

arm 25 mounted on the shaft 23. The contact arm 25, in being carried along by the contact mounting 19 of arm 16, picks up and carries with it the contact arm 26.

The dial is rotated until the number 29 coincides with the marker on the dial and at that point the contact arm 26 is in engagement with its contact pin in the contact plate. The dial is then rotated in the opposite direction, moving the contact arm 16 with it, the contact mounting 19 being constructed, as above stated, so that it clears contact arm 26 and therefore does not disturb its position, until the contact mounting again engages the contact arm 25. The contact arm 25 is moved along by the mounting 19 until the number 27 has been reached on the dial, at which point the contact point of said arm is in engagement with the contact pin 27 in the contact plate 2. The dial 85 is then rotated in the opposite direction again until the contact points of the contact mounting 19 coincide and register with the contact pins 28 in the contact plate. This point is reached when the dial has 90 been rotated until the number 28 coincides with the marker on the dial. The circuit is then closed and ready to function.

It will be seen that a combination of three numbers corresponding to the position of the contact pins in the contact plate must be known to the person who desires to put the circuit in condition for functioning and it is impossible for anyone to close the circuit unless they are acquainted with the 105 combination.

A switch of this character has many desirable uses and may be employed for controlling the ignition circuit of automobiles, for electric locks or for controlling the lighting system of a house, etc.

A preferred embodiment of the invention has been shown, but it will be understood that various changes and modifications may be made without a departure from the spirit and scope of the invention as claimed herein-after.

Having fully described my invention, what I claim as new and desire to secure by Letters Patent is:

1. An electric switch comprising a pair of spaced plates, one of said plates being formed of an insulated material, concentric rows of indentations arranged on said insulated plate, contacts forming the terminals of an electric circuit arranged in certain of said indentations, a shaft secured to said insulated plate, a plurality of contact arms rotatably secured to said shaft and adapted to engage certain of said contacts, the other 120 of said plates having a shaft rotatably secured therein, a contact arm secured thereto and adapted to engage certain other of said contacts, means secured to said shaft for rotating same, and means secured to said shaft 125 for rotating same, and means secured to said last 130

mentioned contact arm for engaging with and actuating the contact arms on said insulated plates.

2. An electric switch comprising a pair of spaced plates, one of said plates being formed of an insulated material, concentric rows of indentations arranged on said insulated plate, contacts forming the terminals of an electric circuit arranged in each of said rows of indentations, a shaft secured to said insulated plate, two contact arms rotatably secured to said shaft, one of said contact arms adapted to engage the contacts in one of said rows of indentations and the other 15 of said contact arms adapted to engage the contacts in another of said rows of indentations, the other of said plates having a shaft rotatably secured therein, a contact arm secured thereto and adapted to engage the contacts in another row of said indentations, means secured to said shaft for rotating said last mentioned contact arm, and means secured to said contact arm for engaging with and actuating the contact arms on said insulated plate.

3. An electric switch comprising a pair of spaced plates, one of said plates being formed of an insulated material, concentric rows of indentations arranged on said insulated plate, contacts forming the terminals of an electric circuit arranged in each of said rows of indentations, a shaft secured to said insulated plate, two contact arms rotatably secured to said shaft, one of said contact arms adapted to engage the contacts in one of said rows of indentations and the other of said contact arms adapted to engage the contacts in another of said rows of indentations, the other of said plates having a shaft 35 rotatably secured therein, a contact arm secured thereto and adapted to engage the contacts in another row of said indentations, means secured to said shaft for rotating said last mentioned contact arm, means secured to 40 said contact arm for engaging with and actuating the contact arms on said insulated plate, a cover for said switch, and means on

said last mentioned plate for securing the switch to a support.

4. An electric switch comprising a supporting plate and an insulated plate, means for spacing said plates apart, concentric rows of indentations arranged on said insulated plate, contacts forming the terminals of an electric circuit arranged in each row of said indentations, a shaft secured to said insulated plate, two contact arms rotatably secured to said shaft and adapted to engage certain rows of indentations and said contacts contained therein, one of said contact 55 arms being shorter than said other contact arm, a shaft rotatably mounted in said supporting plate, a contact arm mounted on said shaft and rotating therewith, a contact mounting mounted on said contact arm, a pair of contact pins arranged in said mounting, and adapted to engage with contacts arranged in a third row of indentations in said insulated plate, means for rotating said shaft, means for rotating the contact arms 60 on said insulated plate when said shaft is rotated, and means for regulating the rotation of each individual contact arm so as to cause the same to engage with or disengage from the contacts in said indentations. 75

5. An electric switch comprising a supporting plate and an insulated plate, means for securing said plates in spaced relation with each other, concentric rows of indentations arranged on said insulated plate, contacts forming the terminals for wires of an electric circuit arranged at predetermined points in said indentations, a contact arm for each of said concentric rows of indentations, one of said arms being adapted to engage 80 the other of said contact arms to thereby move said arms independently one of the other for engaging the contact points at their prearranged points.

In testimony whereof I have hereunto set 90 my hand on this 12th day of June, A. D. 1923.

EDWARD ZEMAN.
